DESIGN FOR A RING OR SIMILAR ARTICLE

Marc Koven, New York, N. Y.

Application May 1, 1947, Serial No. 138,743

Term of patent 3½ years

(Cl. D45—10)

To all whom it may concern:

Be it known that I, Marc Koven, a citizen of the United States, residing at 40 Woodruff Avenue, city of New York, county of Kings, and State of New York, have invented a new, original, and ornamental Design for a Ring, or Similar Article, for which the following is a specification, reference being had to the accompanying drawing, forming part thereof.

Figure 1 is a top plan view of the article.

Figure 2 is a front elevational view of the article, shown in Figure 1.

Figure 3 is a side elevational view of the article, shown in Figure 1.

Although the bottom plan view is not shown, the article is symmetrical and hence the bottom plan view corresponds to Figure 1. Although only

one side view is shown, the article is symmetrical in this respect and hence the side view not shown would correspond to Figure 3.

I claim:

The ornamental design for a ring, or similar article, substantially as shown and described.

MARC KOVEN.
